(57) CLAIM

The ornamental design for glass container for motion lamp, as shown and described.

DESCRIPTION

FIG. 1 is a perspective view of a glass container for motion lamp showing my new design;

FIG. 2 is a side elevation view thereof;

FIG. 3 is a top plan view thereof;

FIG. 4 is a front elevation view thereof;

FIG. 5 is a bottom plan view thereof;

FIG. 6 is an elevation view of side opposite to FIG. 2; and

FIG. 7 is a rear elevation view thereof; and,

FIG. 8 is a perspective view of a glass container for motion lamp; the broken line disclosure of the motion lamp is shown for illustrative purposes only and forms no part of the claimed design.
